UNITED STATES PATENT OFFICE.

OBERT GISERD MANDT, OF KEOKUK, IOWA, ASSIGNOR TO THE AMERICAN CEMENT MACHINE CO., OF KEOKUK, IOWA, A CORPORATION OF IOWA.

CONCRETE MIXER.

Application filed October 8, 1925. Serial No. 61,803.

To all whom it may concern:

Be it known that I, OBERT G. MANDT, a citizen of the United States, residing at Keokuk, in the county of Lee and State of Iowa, have invented certain new and useful Improvements in Concrete Mixers, of which the following is a specification.

This invention relates in general to concrete mixers and more particularly to an improvement in the discharge mechanism employed in conjunction with the mixer for discharging the concrete from the mixing drum of the mixer into a wheelbarrow or other receiver.

The object of the invention is to provide a machine of this character wherein the discharge mechanism is readily and easily controllable in such manner that the discharge chute or spoon may be positioned to receive the concrete from the drum and convey it to the wheelbarrow or receiver or may be positioned in an idle and inactive position and relation with respect to the mixing drum. The discharge chute or spoon is not only shiftable or swingable to operative or inoperative position but is releasably secured in either of its two positions.

A further object resides in the provision of a novel form of operating or control means for the discharge chute or spoon which greatly facilitates the shifting or swinging of the discharge chute or spoon and yet insures the retention of the same in adjusted position. One of the advantages of the control or operating mechanism is that it is operable from either side of the machine.

A still further object resides in the provision of a discharge mechanism for concrete mixers which is of simple and durable construction, reliable and effective in operation and easy and comparatively inexpensive to manufacture.

The present invention consists in the provision in a concrete mixer having a rotary mixing drum provided with a discharge opening of a discharge chute or spoon mounted by means of a pair of arms on a swingable shaft extending transversely and above the discharge opening of the mixing drum, the shaft being rotatable in bearings provided on the frame of the machine so that the discharge chute or spoon may be swung into the discharge opening in the drum in an inclined discharging position

wherein it receives the concrete and permits the same to slide downwardly into the wheelbarrow or other receiver. The discharge chute or spoon may also be positioned or rather swung to a position outwardly of the drum where it is idle or inactive. One of the important features of the invention resides in the novel form of a control means provided for the discharge chute or spoon and co-operable with the shaft on which the spoon or chute is mounted for swinging movement. This control means may consist of a crank arm fixed to the shaft and having a laterally projecting stud, the latter engaging in a three-way slot formed in an operating lever having an adjustable mounting on the frame co-operable from either side of the frame.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in side elevation illustrating one embodiment of the invention applied to a concrete mixer,

Figure 2 is a fragmentary view in elevation looking toward the right of Figure 1, and showing the discharge chute or spoon in idle or inactive position, the control mechanism being correspondingly positioned,

Figure 3 is a view similar to Figure 2 but illustrating the discharge spoon or chute in position to discharge the concrete from the mixing drum, and

Figure 4 is a detail view on the line 4—4 of Figure 2.

Referring to the drawings, the numeral 1 designates generally a concrete mixer which may be of any standard or conventional type and which has a frame 2 on which a rotary mixing drum is mounted and driven in the conventional manner. The rotary mixing drum has a discharge opening 4 and internally has the usual vanes or blades which cascade the mixture and produce a thorough admixture of the ingredients of the concrete.

The present invention proposes the provision of a discharge spoon or chute, designated generally at 10, and comprising a tapered trough-shaped body on which mount-

ing pieces 11 are integrally formed or suitably connected. The mounting pieces 11 are fastened in any suitable way to carrying arms 12 which are curved, as shown in Fig. 2, and which have sleeve members 13 fitted on a shaft 14 and suitably secured thereto. The shaft 14 is rotatably mounted in bearings 15 provided therefor on standards 16 supported on the frame of the machine. 10 When the shaft 14 is rotated in one direction; that is, in a counterclockwise direction, as viewed in Figs. 2 and 3, the discharge chute or spoon 10 will be swung from the position shown in Figure 2 to the position shown in Figure 3. In Fig. 3 the discharge chute or spoon 10 extends through the discharge opening 4 of the mixing drum up into the interior of the drum where it receives the concrete as it falls from the mixing blades 20 or vanes. The concrete falling into the chute or spoon 10 slides down the spoon or chute due to its inclination and falls into a wheelbarrow or other receiver positioned to receive the same. 25 When the discharge spoon or chute 10 is positioned as shown in Fig. 2 it is idle or inactive since it is located out of the field of the concrete that falls from the mixing blades of the drum and is inclined to discharge back into the drum any concrete that may possibly be deposited in the chute or spoon.

Control mechanism is provided for swinging the chute or spoon and for holding the same in adjusted position. This control mechanism includes a crank arm 20 fixed to the shaft 13 adjacent one end of the same. The outer end of the crank arm is provided with a laterally extending stud 21. As 30 shown in Fig. 4, the stud 21 preferably has threaded connection, as at 22, with the outer end of the crank arm 20. The stud 21 also has a head 23 and a smooth bearing portion 24. The smooth bearing portion 24 of the stud is slidably and rotatably fitted in a three-way or T-shaped slot 25 provided in an operating lever 26. The T-shaped slot 25 has a lengthwise portion 27 and lateral portions 28 which 35 extend on both sides of the lengthwise portion at one end of the same. The operating lever 26 is fulcrumed, as at 30, on a bracket 31 secured in any one of the number of possible vertical adjustments on a supporting member 32 by means of fastening devices or bolts 33 co-operable with bolt holes in the bracket 31 and with slots 34 in the supporting member 32. The fastening devices 33 may be either bolts threadedly connected to the bracket 31 having heads engageable with the supporting member 32 or they may be bolts and nuts, the bolts extending 40 through slots in the supporting member 32 and having their heads clamped against the supporting member by means

of nuts threaded thereon. The operating lever 26 is provided with a handle member 40 whereby it may be conveniently shifted or swung to swing and properly position the discharge chute or spoon to carry out the intended phase of the operation. In addition to the handle 40 means is provided for shifting or swinging the operating lever 26 from the opposite side of the machine from that in which the handle 30 is located and this means includes a lateral lug 41 integral with or suitably secured to the operating lever 26 and pivotally connected to one end of a control rod 42 extending to the opposite side of the machine and guided and supported in suitable guides or bearings. If desired, the rod 42 may be equipped with a hand grip or the like at the side of the machine from which it is controlled. 50

With this arrangement when the parts are positioned as shown in Figure 2 the stud 21 is engaged at one end of one of the lateral portions 28 of the slot 25 and this holds the crank arm 20 and the shaft 14 in such position that the discharge chute or spoon 10 is held in the idle or inactive position as shown in Figure 2. To swing the discharge chute or spoon to discharging position and to secure the same in such position, it is only necessary to grab the handle 40 or the grip of the control rod 42 and swing the operating lever 26 in a clockwise direction, as viewed in Figs. 2 and 3 until the operating lever 26 occupies the position illustrated in Figure 3, wherein the stud 28 is engaged with the other branch 28 of the slot 25 and the discharge chute or spoon is held in discharging position. In moving from the position shown in Fig. 2 to the position shown in Fig. 3, the stud first moves out of one of the lateral slots 28 and then down and up in the lengthwise slot 27 and finally into the other lateral slot 28. This operation is reversed during the movement of the discharge chute or spoon from the discharging position shown in Fig. 3 back to the inactive position shown in Fig. 2. 65

I claim:—

1. A chute actuating means for concrete mixers comprising means for mounting the chute for swinging movement whereby it is swingable into co-operative position with respect to the drum and to inactive position relative thereto, means for holding the chute in either position and comprising a crank arm connected with the chute and partaking of movement corresponding to the movement of the chute, an operating lever having a three-way slot, and a stud carried by the crank arm and operating in the three-way slot. 115

2. A chute actuating means for concrete mixers comprising a shaft, a pair of arms fixed to the shaft and carrying the chute, a 120

crank arm fixed to the shaft, a stud carried by the arm, an operating lever having a plurality of slots co-operative with the stud, and means for moving the operating lever from either side of the machine.

3. A chute actuating means for concrete mixers comprising means for mounting the discharge chute for swinging movement, manually controllable means for shifting the discharge chute and holding it in adjusted position and comprising a crank arm connected to the axis of swing of the discharge chute, an operating lever having a slot arrangement therein, a stud connected to the crank arm and co-operative with the slot arrangement of the operating lever, means for moving the operating lever from either side of the machine and including a rod extending from the side of the machine on which the lever is located to the other side of the machine, said lever having a laterally extending lug, said rod being pivotally connected to said lug.

4. A chute actuating means for concrete mixers comprising a shaft adapted to carry the chute, a crank arm fixed to the shaft and having a laterally extending stud at its outer end, an operating lever, an adjustable bracket on which the operating lever is ful-

crumed, said operating lever having a longitudinal slot, lateral slots connecting with one end of the longitudinal slot, the stud of the crank arm being operatively fitted in said slots, and means for moving the operating lever.

5. A chute actuating means for concrete mixers comprising a shaft adapted to carry the chute, a crank arm fixed to the shaft and having a laterally extending stud at its outer end, and an operating lever, said operating lever having a longitudinal slot, lateral slots connected with one end of the longitudinal slot, the stud of the crank arm being operatively fitted in said slots.

6. A chute actuating means for concrete mixers comprising means for mounting the discharge chute for the swinging movement whereby it is swingable into co-operative position with respect to the drum and to inactive position relative thereto, means for holding the chute in either position and comprising a crank arm connected with the chute and partaking of movement corresponding to the movement of the chute, an operating lever having a T-shaped slot, and a stud carried by the crank arm and operating in the T-shaped slot.

OBERT GISERD MANDT.
